The ornamental design for an insect trap, as shown and described.

DESCRIPTION

FIG. 1 is a perspective view of an insect trap according to our design;

FIG. 2 is a front elevation thereof;

FIG. 3 is a rear elevation thereof;

FIG. 4 is a right side elevation thereof;

FIG. 5 is a left side elevation thereof;

FIG. 6 is a top plan view thereof;

FIG. 7 is a bottom plan view thereof;

FIG. 8 is a perspective view of the insect trap of FIG. 1 with the cap removed;

FIG. 9 is a front elevation thereof;

FIG. 10 is a rear elevation thereof;

FIG. 11 is a right side elevation thereof;

FIG. 12 is a left side elevation thereof;

FIG. 13 is a top plan view thereof; and,

FIG. 14 is a bottom plan view thereof.

The broken line showings are included for the purpose of illustrating environment and form no part of the claimed design for an insect trap.
